UNITED STATES PATENT OFFICE.

WILLIAM A. LORENZ, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,158,941.

Specification of Letters Patent.

Patented Nov. 2, 1915.

Application filed April 27, 1908. Serial No. 429,473.

To all whom it may concern:

Be it known that I, WILLIAM A. LORENZ, a citizen of the United States, residing at Hartford, in the county of Hartford and State of Connecticut, have invented certain new and useful Improvements in Type-Writing Machines, of which the following is a full, clear, and exact description, such as will enable others skilled in the art to which it appertains to make and use the same.

This invention relates to typewriting machines, and one of the objects thereof is to provide improved means for feeding the inking ribbon and for changing the direction of the feed thereof.

Another object is to provide mechanism of the above type which may be easily operated, is positive in its operation, and which will operate without noise.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is illustrated one of the various possible embodiments of my invention, Figure 1 is a view in rear elevation of my improved mechanism, partly in section, taken substantially on the line cutting the centers of the vertical shafts shown in Fig. 2. Fig. 2 is a view and plan of the mechanism shown in Fig. 1 with some of the parts removed, the vertical shafts being shown in section. Fig. 3 is a horizontal sectional view taken substantially on line 3—3 of Fig. 1. Fig. 4 is a similar view of one of the ribbon reversing devices with the parts in different positions from those in which they are shown in Fig. 3, the view being taken substantially on line 4—4 of Fig. 1. Fig. 5 is an end view, partly in section looking toward the left end of the mechanism shown in Fig. 2.

Similar reference characters refer to similar parts throughout the several views of the drawings.

Referring now to the drawings 1 represents a shaft which is journaled at either end in the frame of the machine 2 which is shown broken through at the center. This

shaft is driven by means of a pinion 3 from any suitable moving part of the typewriter mechanism, as for instance, the mechanism for moving the platen carriage for letter spacing. Shaft 1 near either end, is provided with gears 4 each of which meshes with a gear 5 on a vertically disposed shaft 6 suitably journaled in the frame of the machine, there being two of these vertical shafts, one on each side of the machine. A handle 7 may be mounted upon the end of shaft 1 by means of which it may be rotated as when it is desired to wind a new ribbon on a spool. It will be understood from the above described construction that whenever shaft 1 is rotated by its driving means, shafts 6 will be driven in opposite directions.

Shafts 6 at their upper ends have fixed thereon pinions 8 by means of pins 9. The ribbon spools or reels 10 are placed upon the upper ends of shafts 6, one upon each shaft. In the present instance, each ribbon spool is provided with a hub 11 slotted as at 12 for receiving the end of the ribbon, which may be secured within said hub by means not shown. Each spool is further provided with lower and upper disks 13 and 14 respectively, the former of which is formed integral with hub 11, and the upper disk rests loosely upon the upper end of said hub and is held in operative position by means of a nut 15, which is threaded upon the upper end of the vertical shaft 6. The hub portions 11 of the spools rest upon the pinions 8 which are secured to shafts 6 and are provided with pinions 16 which lie adjacent pinions 8. The hubs 11 and their pinions are loose upon the vertical shafts 6.

In order to hold the spools 10 upon the vertical shafts 6, said shafts are recessed at 17 and a holding device, which, in the present instance, is constituted by a bent leaf spring 19 is dropped into the interior of the hubs 11, one end of each spring being sprung into a recess 17. This spring will, therefore, normally prevent each hub being removed from each shaft. Such removal, however, may be readily accomplished by disengaging the end of the spring from the upper wall of the recess.

Referring now to the mechanism employed for connecting and disconnecting the ribbon spools to the vertical driving shafts whereby

2
the feed of the ribbon may be reversed, levers or yokes 18 and 20 respectively are pivoted at 21 and 22 to the frame of the machine, one of these levers being provided adjacent each of the vertically disposed shafts 6. Each of levers 18 and 20 is provided with a stud 23 carrying a double pinion 24 which is adapted, when the lever which carries the same is swung to the proper position, to mesh with one set of the pinions provided upon the upper ends of the vertical shaft, and upon the hub of the spool mounted thereon thereby forming an operative connection between these parts, whereby the spool will be rotated with the shaft. Levers 18 and 20 are also provided with depending studs 25, which form pivots for a connecting rod or link 26, the arrangement of the parts being such that when one of said levers is swung to mesh its idler gear with the pinions of a shaft and spool respectively the other thereof will be swung to disengage its idler gear from the corresponding pinions of the other shaft and its spool. Lever 18 is provided with an arm 27 to which is attached a handle 28 by means of which the lever may be swung to engage and disengage its idler gear with or from their pinions, as above described.

30 An outer extension or end of each of levers 18 and 20, in the present instance, is provided with a large notch 30 and a smaller notch 31, and an unnotched curved surface 32. These notches are entered by bent portions 33 of springs 34 and 35 respectively, each of which is secured to the frame of the machine by screws 36 which enter elongated slots thereof, as shown in Fig. 4 of the drawings, the slots being provided to permit the springs to be adjusted for a reason which will be hereinafter apparent. When the bent portion of spring 34 engages the deep notch 33 of lever 18, the idler gear thereof is in mesh with the pinions of the driving shaft and spool respectively upon that side of the machine, as shown at the left hand side of Fig. 2, while spring 35 at the other side of the machine rests upon the unnotched portion 32 of lever 20, whose idler gear is out of mesh with the pinions of the other driving shaft and its spool. With the parts in this position the ribbon will be fed from right to left.

It will be understood that when lever 18 is swung by means of handle 28 the opposite lever 20 will be swung in unison therewith by means of connecting link 26, thereby meshing the idler gear at the right hand of the side of the machine with the pinion of the driving shaft and spool respectively, as shown in Fig. 3 of the drawings, and causing the idler gear upon that side of the machine to occupy a position removed from the corresponding parts of the other driving shaft and spool.

At this point it may be noted that the springs 34 and 35 are so adjusted that the bent ends thereof will hold the levers 18 and 20 in such position as to bring the pinions and the gears of the vertical shafts and spools into mesh without causing the teeth to bottom, thus permitting them to operate without noise. The smaller notches 31 of the swinging levers are so disposed thereon that when the springs 34 and 35 are in engagement therewith the levers 18 and 20 will be in such position that both idler pinions will be disengaged from the pinions which they are adapted to connect, and both ribbon spools will, therefore, be free to rotate upon their shafts as shown in Fig. 4, in connection with one spool.

Casings 36 are provided for inclosing the spools and their actuating mechanism, said casings being apertured as at 37 and provided with fingers 38 through which the ribbon is threaded and which operate as guides therefor.

The operation of this mechanism which should be obvious from the above description may be briefly described as follows: It will be understood that shafts 6 are driven in opposite directions whenever shaft 1 is rotated. When one of the springs 34 and 35 engages the larger notch of one of the levers, 95 the pinions upon that side of the machine are in mesh, and the ribbon will be fed in that direction. When it is desired to reverse the feed of the ribbon the handle 28 may be manipulated to swing its lever 100 whereby the other lever will swing in unison, thereby engaging the other pinion with the gear mechanism on the opposite side of the machine, and causing the ribbon to feed in the opposite direction. When one of levers 105 18 or 20 is swung to disengage its idler gear from the pinions which it is adapted to connect, the positioning spring upon that side of the machine moves upon the smooth surface of the lever as shown in Figs. 2 and 3 110 of the drawings. When it is desired to disengage both gears the idler gears upon both sides of the machine are moved to disengaged position and springs 34 and 35 are brought into contact with the small notches 115 31 on the levers or yokes.

It will accordingly be seen that I have provided mechanism well adapted to attain among others, all the ends and objects above enumerated, in a simple and efficient manner. The mechanism has the further advantage of positiveness of operation, and is so constructed that it will operate without producing noise.

As many changes could be made in the 12 above construction and many apparently widely different embodiments of this invention could be made without departing from the scope thereof, it is intended that all matter contained in the above description or 13

shown in the accompanying drawings shall be interpreted as illustrative and not in a limiting sense.

Having thus described my invention what I claim as new and desire to secure by Letters Patent, is:

6. In a typewriting machine, in combination, a pair of spools adapted to carry an inking ribbon and feed the same in opposite directions across the printing point of the platen, a driving shaft for each of said spools, driving and driven gears upon said shafts and spools respectively, a pair of pivotally mounted levers each carrying an idler gear adapted to be moved into mesh with the gears upon a shaft and spool, and a link connecting said levers whereby they may be swung to engage their idler gears with each set of driving and driven gears in alternation.
2. In a typewriting machine, in combination, a pair of ribbon spools adapted to feed a ribbon past the printing point of the platen, a driving shaft for each of said spools having a driving gear, a driven gear provided upon each of said spools, the gears provided upon each of said shafts and the spool driven thereby lying adjacent each other, a swiveled member located adjacent each of said driving shafts having an idler gear which is adapted to be meshed with the driving and driven gear of said shaft and spool respectively, and a connecting member interposed between said swiveled members whereby they may be swung in alternation to engage or disengage said idler gears with the gears of said shafts and spools respectively.
3. In a typewriting machine, in combination, a pair of shafts each of which is adapted to be driven in opposite directions, said shafts being provided with driving gears, a ribbon spool mounted upon each of said shafts and having a driven gear, a yoke swiveled in the frame of the machine adjacent each of said shafts, an idler gear carried by each of said yokes and a device connecting said yokes whereby they may be swung in alternation to engage or disengage their idler gears with or from the gears of said shafts and spools respectively.
4. In a typewriting machine, in combination, a pair of oppositely driven ribbon spool shafts, a ribbon spool for each of said shafts, driving and driven gears upon said shafts and spools respectively, a swiveled member provided with an idler gear located adjacent each of said shafts, a connection between said swiveled members whereby they may be swung simultaneously alternately to disengage one of said idler gears from one set of driving and driven gears and to engage the other of said idler gears with the other set thereof.
5. In a typewriting machine, in combination, a pair of ribbon spool shafts adapted to be driven in opposite directions, a pair of ribbon spools one for each shaft, driving and driven gears upon each of said shafts and upon each of said spools, means for simultaneously connecting one of said spools with the shaft and disengaging the other thereof from its shaft comprising a pair of swiveled members, one of which is located adjacent either of said shafts, an idler gear carried by each of said swiveled members, and a link connection interposed between said swiveled members.
6. In a typewriting machine, in combination, a pair of ribbon spools, a pair of ribbon spool driving shafts adapted to be driven in opposite directions, driving gears upon said shafts and driven gears upon said spools, a pair of swiveled yokes each of which is provided with an idler gear, each of said yokes being adapted to be swung to engage its idler gear with the driving and driven gears of one of said shafts and its spool, a link connection interposed between said yokes whereby they are swung simultaneously to throw their respective idler gears into or out of operative relation with the gears which are adapted to connect, and means engaging each of said yokes adapted to hold it with its idler gear into or out of mesh with the gears which it is adapted to connect.
7. In a typewriting machine, in combination, a pair of ribbon spools, a pair of ribbon spool driving shafts, one for each spool, gears upon said spools and shafts respectively, the gears of each of said shafts and its spool lying adjacent each other, a swiveled member lying adjacent each shaft provided with an idler gear which is adapted to form an operative connection between the gear thereof and the gear upon the spool, a link interposed between said swiveled members whereby they may swing simultaneously to engage or disengage their idler gears with or from the gears of said shafts and spools, and means engaging each of said swiveled members for holding it in position to engage its idler gear with said first named gears or in a position removed therefrom or in such position that both of said idler gears will be out of mesh with the gears which they are adapted to connect.
8. In a typewriting machine, in combination, a pair of ribbon spool shafts, a pair of ribbon spools one for each shaft, gears upon said spools and shafts respectively, the gears of each spool and its driving shaft lying contiguous to each other, movable idler gears each adapted to be thrown into mesh with a pair of gears upon the driving shaft and spool whereby they are operatively connected, a connection between said idler gears whereby they are engaged or disengaged with the gears which they connect in alternation.

- tion, and a spring member for holding each of said idler gears in such position that the same will be in or out of mesh with said first named gears, said member being also adapted to hold both of said idler gears in a position out of mesh with the gears which they are adapted to operatively connect.
9. In a typewriting machine, in combination, a pair of ribbon spool shafts adapted to be driven in opposite directions, a pair of ribbon spools, one of which is mounted upon each of said shafts, gears upon said spools and shafts respectively, the gears upon which the shaft and spool are mounted being mounted adjacent each other, a yoke swiveled in the frame of the machine adjacent each of said shafts, an idler gear mounted upon each of said yokes and adapted to furnish an operative connection between the gears of each shaft and its spool, a connecting member interposed between said yokes whereby they may be swung alternately and said idler caused to connect or disconnect the gears upon said shaft and spools respectively, each of said yokes being provided with a notch, and a spring member for each of said yokes, which is adapted to enter a notch thereof when the idler gear thereof is engaged with said first named gears whereby said yoke is held against swinging movement.
10. In a typewriting machine, in combination, a ribbon spool shaft, a spool mounted thereon, driving and driven gears upon said shaft and upon said spool respectively, an idler gear adapted to mesh with each of said gears, and means adapted to regulate the depth of the engagement of the teeth of said idler gear with said first mentioned gears.
11. In a typewriting machine, in combination, a ribbon spool driving shaft, a spool mounted loosely thereon, driving and driven gears upon said shaft and spool respectively, a lever carrying an idler gear adapted to be swung, whereby said idler gear may mesh with both of said first mentioned gears and effect an operative connection therebetween, and an adjustable spring which engages said lever adapted to hold said idler gear so that the teeth thereof will not bottom with the teeth of the gears with which it meshes.
12. In a typewriting machine, in combination, a pair of ribbon spool shafts, a spool loosely mounted upon each of said shafts, driving and driven gears upon said shafts and spools respectively, a pair of swiveled levers, one of which is located adjacent each of said shafts, an idler gear mounted upon each of said levers, and means connecting said levers whereby they may swing in unison alternately to mesh or disengage their idlers from the gears upon said shafts and spools whereby the direction of feed of the ribbon will be reversed.
13. In a typewriting machine, in combination, a pair of ribbon spool shafts, a spool mounted upon each of said shafts, driving and driven gears upon said shafts and spools respectively, a pair of movable members each of which carries an idler gear which is adapted to mesh with one pair of driving and driven gears whereby they may be operatively connected, a connection between said movable members whereby they may be operated in unison, and means for holding either of said movable means in such position that its idler gear will be in mesh with one pair of driving and driven gears, said means also operating to hold both of said movable members in such position that both idler gears will be out of mesh with the gears which they operatively connect.

In testimony whereof I affix my signature in the presence of two witnesses.

WILLIAM A. LORENZ.
